[57] **CLAIM**

The ornamental design for a truck visor, as shown and described.

DESCRIPTION

FIG. 1 is a perspective view of a truck visor showing our new design, it being understood that the broken lines are for illustrative purposes only to illustrate the environment in which the visor will be used and form no part of the claimed design;

FIG. 2 is a front elevational view thereof;

FIG. 3 is a top plan view thereof;

FIG. 4 is a rear elevational view thereof;

FIG. 5 is a bottom plan view thereof;

FIG. 6 is a side elevational view thereof;

FIG. 7 is a vertical sectional view taken substantially along line 7—7 of FIG. 4; and,

FIG. 8 is a vertical sectional view taken substantially along the line 8—8 of FIG. 4.

FIG. 2

FIG. 1
